UNITED STATES PATENT OFFICE.

ANDREW DRENGSON, OF THOMPSON, (DAKOTA TERRITORY,) NORTH DAKOTA.

CAR-COUPING.

SPECIFICATION forming part of Letters Patent No. 415,449, dated November 19, 1889.

Application filed April 19, 1889. Serial No. 307,726. (No model.)

To all whom it may concern:

Be it known that I, ANDREW DRENGSON, of Thompson, in the county of Grand Forks and Territory of Dakota, have invented a new and Improved Automatic Car-Coupler, of which the following is a full, clear, and exact description.

This invention relates to car-couplers, the object of the invention being to provide a coupler which will couple automatically and which may be manipulated without entering the space between the ends of the cars, whereby all danger of the crushing of the train-hands is avoided and the coupling of the cars constituting a train is easily brought about.

To the end named the invention consists, essentially, of a draw-head in which there is pivotally mounted a coupling-hook, said draw-head being provided with an open recess adapted to receive the coupling-hook of a corresponding coupler, and a hook-raising device arranged within the draw-head, all as will be hereinafter more fully explained, and specifically pointed out in the claim.

Reference is to be had to the accompanying drawings, forming a part of this specification, in which similar figures and letters of reference indicate corresponding parts in all the views.

Figure 1 is a perspective view of a portion of a car, representing the same as it appears when provided with my improved coupler. Fig. 2 is a longitudinal sectional view of two couplers constructed in accordance with the terms of my invention, the parts being represented as they appear when in the coupled position, and Fig. 3 is a cross-sectional view on line $x-x$ of Fig. 2.

In the drawings, 10 represents a draw-head formed with a recess 11, which extends through the upper wall of the draw-head. Through this recess there is passed a transverse pin 12, which bears against a face 13, formed as shown in Fig. 2, the pin 12 serving as a wear-pin, against which the coupling-hook of the opposing coupler bears. The opposite side of the coupler 10 is recessed at 13, and in the recess so formed there is mounted a coupling-hook 14, said hook being fulcrumed on a transverse pin or bolt 15, and normally held in the position in which it is shown in the drawings by a spring 16.

In the lower portion of the draw-head is mounted a block 17, which is connected to an upwardly-extending stem 18, to which stem 55 there is connected a chain 19, that extends to a vertical shaft 20, having a hand-wheel 21, said hand-wheel being located in proper position to be operated from the tops of the cars; or the wheel might be located in any 60 other convenient position. In passing from the stem 18 to the shaft 20 the chain 19 runs upon a sheave 22, that is supported by a standard 27, said standard being secured to the draw-head. 65

Such being the general construction of my improved coupler, it will be seen that as two cars provided with such couplers approach, the coupling-hooks, which are formed with inclined faces a , will strike against the flaring 70 mouths b of the opposing draw-heads and will ride up over said flaring mouths b , over the pins 12, to the position in which the parts are shown in Fig. 2, the hooks engaging the pins 12 of the opposing draw-heads, as will 75 be readily understood.

To uncouple the cars, the shaft 20 is turned and the block 17 is raised, which movement of the block will throw the coupling-hooks from engagement with their pins 12. 80

With such a coupler as the one above described all the cars of a train may be coupled by simply bringing them together, and to uncouple the cars there is no necessity of the train-hands entering the space between the 85 cars.

Having thus described my invention, I claim as new and desire to secure by Letters Patent—

In a car-coupler, the combination, with a draw-head formed with recesses 11 and 13, 90 of a coupling-hook pivotally mounted within the recess 13, a transverse block which extends beneath the coupling-hook and into the recesses 11 and 13, a stem extending upward from the block, a chain connected to the stem, 95 and a shaft upon which the chain is wound, substantially as described.

ANDREW DRENGSON.
